United States Patent Office.

WILLIAM A. SHEPARD, OF CHICAGO, ILLINOIS.

Letters Patent No. 105,135, dated July 5, 1870.

IMPROVED FOUNTAIN-BRUSH HOLDER.

The Schedule referred to in these Letters Patent and making part of the same.

To whom it may concern:

Be it known that I, WILLIAM A. SHEPARD, of Chicago, in the county of Cook and State of Illinois, have invented a certain new and useful Fountain brush Holder, of which the following is a specification.

My invention is intended for the purpose of conveying a constant stream of water or other fluids to tooth-brushes, nail, or hair-brushes, so as to keep such brushes constantly supplied with liquid when in use; and, to this end

It consists in the use with the brush of a tube of flexible or elastic and pliable material, one end of which is adapted to be attached to a faucet or reservoir, or other source of water supply, and the other is provided with a pocket or sleeve, or formed in an equivalent manner, as hereinafter described, to fit upon the brush-handle, so that water may pass constantly from the reservoir or faucet to the brush in such quantity as may be desired.

The manner in which my invention is or may be carried into effect will be readily understood by reference to the accompanying drawing, which represents a perspective view of a tooth-brush, provided with a fountain holder, made in accordance with my invention.

The supply-tube *a* is made of vulcanized India rubber, or of other suitable material, and one of its ends, *b*, is funnel-shaped, so that it may be slipped over and fitted tightly upon a faucet, such, for instance, as now placed upon wash-stands in many instances.

In order to connect the supply-tube with the tooth-brush, I make use of a short elastic sleeve or pocket, *c*, of rubber or other suitable material, which is cemented or otherwise secured to the end of the tube from which the water is discharged upon or into the brush.

This pocket is slipped on the brush-handle, which it tightly fits, until the end of the supply-tube is very near or in contact with the bristles of the brush.

If, now, the faucet, with which the funnel-shaped end of the tube is connected, be opened, a constant stream of water will be supplied to the brush, and the flow of water can be maintained so long as the brush is in use.

The flow of water can be regulated by opening the faucet more or less.

The length of the tube should be sufficient to allow the brush to be used freely without danger of pulling on the tube, and the tube may be of small diameter, for instance, the size shown in the drawing, which is sufficient to keep the brush amply supplied with water.

Instead of using the pocket *c* for holding the end of the tube on the brush, the pocket can be dispensed with, and the end of the tube can be made larger, so as to slip on the brush-handle, in which case ridges can be formed on the inside of this portion of the tube, so as to leave spaces or channels between the tube and the handle, for the water to flow through to the brush, or the ridges on the tube may be dispensed with, and grooves cut in the handle.

The tube may also be attached to the faucet, reservoir, or other source of water supply, by means of a coupling, instead of the funnel-shaped end *b*.

I much prefer, however, the fountain brush-holder constructed as shown in the drawing, as it is inexpensive, can be readily applied to or detached from the brush and faucet, and can be used with a brush or faucet of any ordinary construction.

As above stated, my invention is applicable to nail and hair-brushes as well as to tooth-brushes, and may also be used with bathing-brushes and other like articles.

Having now described my invention, and the manner in which the same is or may be carried into effect,

What I claim, and desire to secure by Letters Patent, is—

The water or liquid-supply tube, provided at one end with a pocket, to fit upon the brush-handle, and adapted to be connected at the other end with a faucet or other source of water supply, substantially as set forth.

In testimony whereof I have signed my name to this specification before two subscribing witnesses.
